DESIGN FOR A DEVICE FOR VENDING MACHINES

Carl R. Simpkins, Inglewood, Calif., assignor to
John Franklin Meyer, Pasadena, Calif.

Application October 16, 1936, Serial No. 65,327

Term of patent 3½ years

To all whom it may concern:

Be it known that I, Carl R. Simpkins, a citizen of the United States, residing at Inglewood, in the county of Los Angeles and State of California, have invented a new, original, and ornamental Design for a Device for Vending Machines, of which the following is a specification, reference being had to the accompanying drawing, forming a part thereof, wherein

Fig. 1 is a perspective view of the device for vending machines illustrating my new design; and

Fig. 2 is a plan view of the device for vending machines shown in Fig. 1.

I claim:

The ornamental design for a device for vending machines, as shown.

CARL R. SIMPKINS.
